UNITED STATES PATENT OFFICE

2,040,950

ADVERTISING DEVICE

Richard F. Outcault, Flossmoor, Ill.

Application August 15, 1934, Serial No. 739,875

8 Claims. (Cl. 40—126)

This invention relates to an advertising device and more particularly to a device employing a figure having a mechanically operated portion to attract attention and create interest.

An object of the invention is the provision of a mechanically operated advertising device in which a figure such as the simulation or representation of a man is employed, for example, and in which a mechanically operated figure is formed in a unitary structure with a supporting member for the operating mechanism to enable the entire assembly to be adapted to a variety of uses by a mere change in position or association with the article to which attention is desired to be drawn.

Further objects of the invention reside in providing improved means for operating a mechanically actuated figure.

An additional object of the invention is the provision of means for removably supporting a unitary mechanically operated advertising device particularly in association with an advertising medium such as a sign or circular.

A further object is the provision of improved means for supporting a mechanically actuated advertising device in association with stands, cartons, boxes, et cetera.

Other objects will appear hereinafter.

The invention consists in the combinations and arrangements of parts hereinafter described and claimed.

The invention will be best understood by reference to the accompanying drawings forming a part of this specification, and in which:

Fig. 1 is a front elevational view of a preferred embodiment of the invention showing a figure having a mechanically operated arm and pointing hand to act as an indicator, arranged on a unitary structure with a supporting plate for the operating mechanism and for the figure;

Fig. 2 is a perspective view of a display frame designed to be used in one adaptation of the invention;

Fig. 3 is a front elevational view of the device employed in conjunction with the frame shown in Fig. 2 and operating in conjunction with any selected carton or box for attracting attention to the display;

Fig. 4 is a vertical sectional view taken substantially on the line 4—4 of Fig. 3;

Fig. 5 is a slightly different adaptation of the device in which the figure is in standing position and the device used in association with a stand or frame for an advertisement or display;

Fig. 6 is a side view of the assembly shown in Fig. 5;

Fig. 7 is a horizontal sectional view taken substantially on the line 7—7 of Fig. 5;

Fig. 8 is a rear view of the advertising or display stand used in association with the unitary device of the invention as shown in Fig. 5;

Fig. 9 is a vertical sectional view of the stand taken on the line 9—9 of Fig. 8;

Fig. 10 is a vertical sectional view taken substantially on the line 10—10 of Fig. 1, with the movable arm shown in section to disclose the connection of the arm clamping means; and

Fig. 11 is a vertical sectional view of the figure employed taken substantially on the line 11—11 of Fig. 7.

Referring now to the drawings, particularly to Fig. 1, the preferred embodiment of the invention comprises a figure 14, which, as shown, may be designed to represent a doll or clown having a horizontally reciprocable hand 15 and mounted as a unitary structure or assembly in association with a mounting plate 16. Plate 16 is preferably secured to the figure 14 by means of a connecting portion 17 of an encircling band or belt 18 adapted to act as a stiffening and supporting member and bolted to the plate 16 as shown in Fig. 7 to properly maintain the parts in definite spaced relationship. Encircling belt 18 is preferably covered with a concealing fabric material 19 which serves to effectively cover and conceal the band 18 and avoid outward appearances the rigid unitary structure between the figure or model 14 and the mounting plate 16 with the associated operating mechanism.

The figure or model 14 may be of fabric construction, preferably with a filler of compressed hair 20 or similar material, so that the model is of sufficient durability and rigidity in the usual operation, but the loose hand 21, legs 22, and head 23 are sufficiently flexible to be placed in various positions and remain in such selected positions by reason of the general construction described.

Mounted rearwardly of the mounting plate 16 is the operating means, consisting preferably of an electric motor 24 having the usual cord 25 and connecting plug 26. As shown, the motor 24 may be bolted or otherwise secured to the mounting plate 16, and the operating shaft which preferably extends through plate 16 to the forward side carries a crank arm 27 to which is pivotally connected one end of link 28, the opposite end of which is pivotally connected to bar 29 integrally formed with an inner enlarged portion of arm clamp 30 so as to form on a small scale a character of cross head arranged for reciprocating motion within U-shaped guide member 31 mounted upon

the forward side of plate 16, as shown in Figs. 7 and 10. The clamp 30 is looped to engage the flexible movable arm of the figure or model 14. By this construction and arrangement the flexible model, the mounting plate for the operating mechanism, and the operating mechanism itself are integrally and conveniently assembled as a unit whereby the device may be conveniently employed for a variety of purposes and quickly installed in many places, in a crowded show window for example, which would be practically inaccessible or difficult and time-consuming with the usual constructions. To facilitate use of the device for different purposes the upper and lower edges of the mounting plate 16 are preferably bent forwardly and then outwardly in the same plane to produce attaching flanges 32 and 33 preferably perforated as at 34 for the reception of connecting bolts or similar devices.

20 For example, plate 16 may be bolted to the frame or standard 35, shown in Fig. 2, which has a lower horizontal portion 36 and a vertical portion 37. The lateral and bottom edges of the portion 37 are preferably flanged as at 38 for the reception of signs, notices, or various advertising media. Perforations 34 of plate 16 are arranged to register with openings 39 of the vertical portion 37 of standard 35 for convenient attachment.

One practical adaptation of the device is shown 30 in Figs. 3 and 4, in which plate 16 is connected to standard 35 for the purpose of supporting the device, one edge of an ordinary merchandise carton 40 having matter of advertising value on the front face is slotted vertically for the insertion 35 of the connecting portions between plate 16 and the model supporting belt 18, and legs 22 of the figure 14 bent forwardly to a sitting posture after the assembly has been incorporated with the advertising carton or box 40 as described. In this 40 employment of the device the model 14 assumes the position shown in Fig. 3 alongside the carton, motor 24 is started, and the pointing hand 15 with the operating mechanism concealed continuously reciprocates horizontally in such manner as not 45 to obstruct a view of the matter to which attention is desired to be directed.

Another convenient adaptation of the device is illustrated in Figs. 5 and 6, using the stand 41 shown in Figs. 8 and 9 which has a face portion 42 adapted to be supported in an upright position by rearwardly extending braces 43 and 44 connected to support 45. As shown in Fig. 9, brace 43 may be bolted to support 45, and the forward extremity which engages the stand 41 55 is preferably detachably mounted by a hook 46 which engages the upper edge of stand 41. A similar detachable arrangement for the bottom brace 44 is provided by hingedly connecting one end to support 45 at 47, and the forward end of brace 44 60 is provided with a downwardly turned flange 48 adapted to detachably engage a complementary flange 49 arranged adjacent the bottom of stand 41. The entire forward portion of face 42 is preferably flanged along the lateral edges and along 65 the bottom edge, as at 50, for the reception of such placard, sign, notice, or advertisement as may be desired. Face portion 42 is also preferably sheared to provide at the rear thereof flanges 51 for the reception and engagement of flanges 32 70 and 33 of mounting plate 16. By the construction shown the model 14 assumes a standing position, hand 21 is rested upon the upper edge of the stand 41, and no bolting or other connection of the stand 41 to plate 16 is necessary inasmuch as the 75

latter is securely held by reason of the engagement of the flange members 51. Similarly, in this adaptation or employment, the operating mechanism is entirely and conveniently concealed and the movable hand 15 is arranged to reciprocate continuously a short distance depending upon the throw of crank 21, along one edge of stand 41 to attract and direct attention.

While I have described and illustrated the preferred form and construction for carrying my invention into effect, this is capable of variation and modification without departing from the spirit of the invention. I, therefore, do not wish to be limited to the precise details of construction as set forth, but desire to avail myself of such variations and modifications as come within the scope of the appended claims.

Having thus described my invention, what I claim as new and desire to secure by Letters Patent is:

1. A device of the character described, comprising a model, a movable member on said model, a supporting band on said model, a mounting plate arranged adjacent said model, a rigid connection between said band and said mounting plate, operating mechanism mounted upon said mounting plate, and an operative connection between said operating mechanism and said movable member.

2. A device of the character described, comprising a model, a movable member on said model, a supporting band on said model, a mounting plate arranged adjacent said model, a rigid connection between said band and said mounting plate, operating mechanism mounted upon said mounting plate, an operative connection between said operating mechanism and said movable member, and means for connecting said mounting plate to a standard for display purposes.

3. In combination, a model of the character described, a standard adapted to receive and support matter for display purposes, a movable member on said model, a mounting plate arranged adjacent said model and secured thereto, operating mechanism mounted upon said mounting plate, an operative connection between said operating mechanism and said movable member, and means for detachably securing said mounting plate to said standard.

4. In combination, a model of the character described, a standard adapted to receive and support matter for display purposes, a movable member on said model, a mounting plate arranged adjacent said model, means connecting said standard and said mounting plate, a supporting band on said model, a rigid connection between said band and said mounting plate, operating mechanism mounted upon said mounting plate, and an operative connection between said operating mechanism and said movable member.

5. A device of the character described, comprising a model, a movable member on said model, a mounting plate arranged adjacent said model and secured thereto, a guide member mounted upon said model, a clamping member connected to said movable member and having a portion slidably mounted in said guide member, operating mechanism mounted upon said mounting plate, and an operative connection between said operating mechanism and said clamping member.

6. A device of the character described, comprising a model, a movable member on said model, a mounting plate arranged adjacent said model and secured thereto, a guide member mounted upon said model, a clamping member connected to said movable member and having a portion slidably mounted in said guide member, operating mechanism mounted upon said mounting plate, and an operative connection between said operating mechanism and said clamping member.

to said movable member and having a portion 5
slidably mounted in said guide member, operating
mechanism mounted upon said mounting plate,
an operative connection between said operating
mechanism and said clamping member, and
means for connecting said mounting plate to a
standard for display purposes.

7. A device of the character described, comprising a model, a movable member on said model, 10
a supporting band on said model, a mounting plate arranged adjacent said model, a rigid connection between said band and said mounting plate, a guide member mounted upon said model, a clamping member connected to said movable 15
member and having a portion slidably mounted in said guide member, operating mechanism mounted upon said mounting plate, an operative connection between said operating mechanism and said clamping member, and means for connecting said mounting plate to a standard for display purposes.

erative connection between said operating mechanism and said clamping member.

8. A device of the character described, comprising a model, a movable member on said model, a supporting band on said model, a mounting 5
plate arranged adjacent said model, a rigid connection between said band and said mounting plate, a guide member mounted upon said model, a clamping member connected to said movable 10
member and having a portion slidably mounted in said guide member, operating mechanism mounted upon said mounting plate, an operative connection between said operating mechanism and said clamping member, and means for connecting said mounting plate to a standard for 15
display purposes.
